SAFETY LINK

Robert L. Hohler, Dayton, Ohio

Application May 9, 1945, Serial No. 592,849

6 Claims. (Cl. 209—35)

1

This invention relates to safety links and more particularly to links to prevent overloading hoists and electric hoisting apparatus.

In the use of electrical hoisting apparatus by which objects are raised or moved, as in manufacturing plants handling metals or other heavy objects, accidents and injuries sometimes occur to workmen as well as considerable damage to equipment due to the fact that failure occurs when attempts are made to lift greater loads than those for which the hoist or hoisting apparatus were designed.

It is, therefore, important to provide a means which will operate, when excessive loads are encountered to open an electric circuit to the control instruments of the hoisting apparatus before overloading of the hoist or hoisting equipment occurs.

An object of the present invention is to provide means whereby the hoisting apparatus shall automatically stop when an overload exists.

Another object of the present invention is to provide a link which can be calibrated to suit a particular operation, not necessarily the maximum capacity of the hoist. This is accomplished by having the switch mounted relative to an adjustable arm which actuates the switch. The link is then calibrated by elongating same to a given load and then securing the arm to operate the switch at this load.

Another object of the present invention is to provide a link with an electrical switch therewith which may be operated at a predetermined load to open a circuit to the control device of the hoisting apparatus when said predetermined load is reached and at the same time so designed and arranged that the switch will not be actuated when load is below the predetermined load.

A more specific object of the present invention is to provide an elongated loop spring with a sensitive switch mounted thereon and connected electrically to the hoist controls which may be operated at a predetermined load to open a circuit to the electrical control device for the hoisting device. The switch is mounted in a manner that at a predetermined load or overload applied to the cable the link will elongate a certain amount causing the switch to be actuated and open the circuit to the hoist controls. The link is calibrated to elongate a certain amount with a given load or when an obstruction is encountered before the switch is operated so that there is no danger of the switch being operated too soon to stop the hoisting apparatus when safe loads are being lifted.

2

Further objects and advantages of the present invention will be apparent from the following description, reference being made to the accompanying drawings wherein a preferred embodiment of the present invention is clearly shown.

In the drawings:

Fig. 1 is an end view of the link embodying the present invention.

Fig. 2 is a side view looking in the direction of arrow 2 in Fig. 1.

Fig. 3 is an end view of a modified form of the present invention.

Fig. 4 is a side view looking in the direction of arrow 4 in Fig. 3.

Fig. 5 is a sectional view taken on line 3—3 of Fig. 3.

Fig. 6 is a sectional view of the switch.

Fig. 7 is a fragmentary plan view of a modified form of spring member.

Fig. 8 is a sectional view taken in line 8—8 of Fig. 7.

Referring to Figs. 1 and 2, 20 designates a link device including attachment blocks 21 and 22. The block 21 in this instance is provided with a tapered opening 23 to receive a leadend 24 of a cable 25 while the block 22 is provided with a closed eye 26. It is to be understood that the block 21 could be formed with a closed eye to receive a hook (not shown) pivotally suspended from a stationary member associated with the hoist apparatus.

A pair of preformed spring members 30 and 31 having bowed portions 32 and 33, respectively, are secured on opposite sides of the blocks 21 and 22 by bolts 34. It is to be understood that any number of spring members can be used. Each bolt has a shank passing through aligned apertures provided by the blocks and the ends of the spring members. Each bolt has a head engaging a spring or lock washer 35 engaging the outer face of spring member 30, and a nut 36 engaging a spring or lock washer 37 engaging the outer face of the spring member 31. By setting the nuts, the spring members 30 and 31 are securely attached to the blocks 21 and 22 to form a loop. These springs are arranged in this instance so that the bowed or arched portions 32, 33 oppose each other and, said arched portions being of such character that when tension is applied to the ends thereof and longitudinally of the spring the sides will move transversely and approach each other. It is to be understood that the spring members could be mounted so that the bowed portion may be reversed from that shown in the drawings.

55 The block 21 in this instance is provided on one

end thereof with a longitudinal groove 40 to receive one arm 42 of an adjustable L-shaped bracket 41. A screw 43 which passes through an elongated slot 44 in the arm 42 which will, when tightened, secure the bracket 41 to the block 21 in the desired position of adjustment. The other arm 45 of the bracket 42 extends between the spring member.

Mounted upon the lower side of the block 22 is an electric switch 50 of the snap-acting type. One form of switch construction and arrangement of elements is shown in Fig. 6. It is to be understood other forms could be used. In the switch shown the switch comprises a base 51 closed by a cover 52 for enclosing the switch mechanism. A threaded insert 53 is embedded in the base. A screw 54 having a threaded engagement with the insert 53 secures an anchor washer 55. The insert provides an electrical connection between the washer 54 and an external screw 56. The washer 55 supports a snap-acting element or contact member 57 which when pressure is applied at 57a the element moves with a snap action between a stationary contact 58 and a non-conducting abutment 59 carried by the base made of insulating material. The contact 58 is electrically connected with an insert 60 embedded in the base, said insert 60 provides an electrical connection between the stationary contact 58 and the external screw 61.

The element 57 is mounted in cantilever fashion by the screw 54 and the element is constructed so that when pressure is applied to the element 57 at 57a by a plunger 62 slidably supported in a guide opening provided by the cover 52 the element 57 will snap into engagement with the stationary contact 58, but when said pressure is released the element will snap out of engagement with the stationary contact 58. Fig. 6 shows the relative position of the element 57 after the pressure has been applied. Since any type of snap-acting switch construction can be used with the link, specific detailed description of the switch parts is deemed unnecessary. The switch 50 is enclosed within a protecting metal cover 63, said cover is held in position by screws 64. The screws 64 pass through holes in the base and have threaded engagement with tapped holes provided by a bracket 65.

Before the cover 63 is secured in position, one end of leads 66 and 67 are electrically connected with inserts 53 and 60 by screws 56 and 61 respectively. These leads 66—67 preferably extend out through a rubber grommet or the like with the other ends thereof connected with respective terminals, not shown, of a suitable control switch for controlling the up or lifting operations of the hoist apparatus.

With the parts arranged as shown in Fig. 1 the upper end of the loop spring member 20 is attached to a fixture while the lower end is attached to a cable 25 so that when a predetermined load is to be lifted by the cable the lateral movement of the sides will not be sufficient to permit the arm 45 to move far enough to allow the switch 50 to operate, thus the load can be lifted with safety. When, however, obstructions are encountered or excessive loads are tried to be lifted by the cable 25 the cable will pull the block 21 downwardly against the tension of the springs 30 and 31 causing the bowed portions 32 and 33, respectively, of the springs 30 and 31 to approach each other. This downward movement of the block 21 carries the bracket 41 with it, thus when the block has moved a certain distance downward,

as viewed in Figs. 1 and 2, the element 57 will snap out of engagement with the stationary contact 58 to open a circuit to an up-control switch (not shown) for the hoisting apparatus. When the 5 overload has been relieved the link-switch will automatically close thus permitting the up-control switch to be reset. It is to be understood that the links can be mounted in many other ways so long as the link proper is arranged to permit elongation thereof. For example, when a chain is used the link can be mounted between the hoist dollies or hanger and the hoist proper.

If desired the link may be enclosed within a steel casing 68. The top wall 69 and the bottom wall 69a have notches through which the eye 26 and cable 25 project. The bottom wall 69a acts as a stop to limit the amount of movement of elongation of the link.

In the modified form shown in Figs. 3, 4, 5, and 6 a link comprises a set of spring members 70 and 71 having bowed portions 72 and 73 respectively. The opposed ends of the spring members engage each other and said ends together with suitable plates are secured together by welding or in any other suitable manner. In this present instance apertured plates 74 and a pair of semi-circular members 75 are arranged on opposite sides of the spring ends and welded together. The plate ends are provided with apertures which align with the 20 apertures in the ends of the spring members 70—71, said apertures receiving a cable, hook or shackle attached to a stationary element. The lower ends of the spring members 70—71 are also secured together by welding two apertured washers or plates disposed on opposite sides of the ends. The apertures of the plates align with the apertures provided by the spring ends to receive a cable. The cable is threaded through the apertures and then clamped in any suitable manner 30 such as a U-bolt. The bowed portion 72 of the spring member 70 supports a switch 50 having the biased plunger 62 while the bowed portion 73 of the spring member 71 supports an adjustable screw 76 having a tapered end 77 normally spaced 35 from the end of the actuator 62 located outside the cover 52. The screw is held in an adjustable position by a lock nut 82.

With the parts as thus arranged, as viewed in Fig. 3, the upper end of the link when attached 50 to a fixed part, not shown, and the lower end to a cable 25, any normal strains, while tending to cause the bowed portions 72 and 73 to approach each other will not be sufficient to cause the tapered portion 77 of the screw to actuate the plunger 62. However, when an excessive load is attempted to be lifted or an obstruction is encountered the bowed portions 72—73 will approach each other sufficiently to cause the tapered portion of screw 77 to cam the plunger 62 inwardly to apply pressure at the point 57a to cause the element 57 to move with a snap action to move same out of engagement with the stationary contact 58 and engage the abutment 59.

Referring to Figs. 7 and 8 a fragment of a modified form of arced shaped spring members 89 adapted to be connected to blocks 21 and 22 is shown. When this type of spring member is used, the blocks 21 and 22 are provided with 60 extensions or lugs 90. Each spring member 89 is hingedly connected with the blocks 21 and 22 by hinge pins or bolts 91 around which ends of the spring member are bent.

In the operation of the link devices thus 75 described, it will be assumed that the link switch

is connected electrically with a locking type relay switch with a reset feature and the relay is in turn connected in series with the electrical up-control device for the hoist apparatus. Let it further be assumed that the link switch is associated with a 1000 pound capacity cable hoist. On a 1000 pound capacity hoist with a one sheave load block, the link can be set for 750 pounds which will give a 1500 pound capacity maximum loading. That is, when a load is lifted effecting a 1500 pound or more on the spring link, the link will elongate causing the spring link switch to operate to open the circuit to the lock out relay switch which in turn will break the circuit to the up-control device of the hoist. The down-control position of the control device for the hoist will not be effected. Thus, the down control of the control device can function to relieve the overload. When the overload has been relieved, the lock out switch can be reset to put all of the switches in their normal positions. By this arrangement the operator must call an electrician to reset the lock-out relay. It is to be understood that the lock-out relay switch could be omitted.

While the embodiment of the present invention as herein disclosed, constitutes a preferred form, it is to be understood that other forms might be adopted, all coming within the scope of the claims which follow.

What is claimed is as follows:

1. A safety link apparatus comprising, a set of preformed spring members; means for securing the ends of the spring members together to form a loop with the sides thereof adapted to move relative to each other under tension, one end of the loop adapted to be attached to a stationary member while the other end is adapted to be connected to a means capable of lifting a predetermined load; a switch carried by one of the spring members for controlling a circuit, said switch including a relatively stationary contact and a movable contact arranged in a certain relation when the spring members are in their normal position; and an adjustable plunger for the switch carried by the other spring member, said spring members moving relative to each other when the spring members are subjected to stresses equal to or above the adjusted setting of the plunger to cause the plunger to change the relation of the contacts due to elongation of the spring members.

2. A safety link apparatus comprising, an elongated spring member having spaced sides capable of moving toward each other under tension, one end of the spring member capable of being fixed to a stationary member and the other end adapted to be attached to a movable member; a switch having a biased contact and a relatively stationary contact carried by the spring member; adjustable means carried by the spring member for holding the movable contact in engagement with the stationary contact to complete a circuit, said adjustable means adapted

to be moved by the elongation of the spring member when the spring member is subjected to abnormal stresses and thereby permit the biased contact to move out of engagement with the stationary contact by its own resiliency.

3. A safety link apparatus comprising, a plurality of bowed leaf springs; a pair of spaced blocks; means for securing opposite ends of one or more leaf springs to opposite sides of the blocks to form a closed loop, said spring being capable of moving relative to each other under stress, one end of the loop adapted to be attached to a stationary member while the other end is adapted to be affixed to a means capable of lifting a predetermined load; a switch carried by the loop, said switch including a stationary contact, a biased contact, and a plunger; an adjustable bracket carried by the loop and having an arm engaging the plunger causing same to hold the biased contact into engagement with the stationary contact when the load is at or below the predetermined load said springs moving relative to each other when an excess load is imposed upon the loop to move the arm from the plunger and permit the biased contact to move out of engagement with the stationary contact to open the circuit; and means for limiting the movement of the leaf spring.

4. A safety link according to claim 3 in which the opposite ends of the bowed leaf spring members are hingedly connected on opposite sides of the block.

5. A safety link apparatus comprising; in combination a relative stationary member; a relative movable member; a plurality of bowed leaf springs arranged in parallel; means for securing opposite ends of the leaf spring to the members; an electric switch; means for supporting the electric switch for actuation by relative movement of the members; and means actuated upon flexing of the leaf springs for actuating the switch.

6. In an electrical hoist apparatus, the combination comprising; a safety link for connecting a load to a hoist apparatus, said link including a relative fixed member and a relative movable member; bowed spring members arranged in parallel to connect the fixed member with the movable member and adapted to flex upon application of load to the link; an electric switch device for indication of overload; means for supporting the switch device so as to be actuated upon flexing of the springs; and means operated by applying the load to the link for actuating the switch.
